(57) CLAIM

The ornamental design for a one-piece swimsuit, as shown and described.

DESCRIPTION

FIG. 1 is a front view of a one-piece swimsuit showing my new design;

FIG. 2 is a rear view thereof;

FIG. 3 is a left side view thereof; and,

FIG. 4 is a right side view thereof.

The broken lines outline of a model assists in illustrating how the one-piece swimsuit may appear when in a position of use, but forms no part of the claimed design. The evenly spaced broken lines depict features of the one-piece swimsuit that form no part of the claimed design. The dot-dash broken lines define the bounds of the claimed design and form no part thereof.
